BOOKBINDING

Otto W. Sutter, Fond du Lac, Wis., assignor to
American Type Founders, Inc., Elizabeth, N. J.,
a corporation of New Jersey

Application August 26, 1942; Serial No. 456,246

4 Claims. (Cl. 154—41)

This invention relates to book binding and more particularly to the securing of stripping to the leaves prior to applying and securing the cover of the book in place, and has for the primary object the provision of a simple, efficient and inexpensive machine capable of supporting and moistening the binding material as used and for guiding the assembled or stapled leaves of the book with the binding material engaged therewith under pressure to bring about tight adhesion of the binding material with the leaves and for cutting the binding material in proper lengths in accordance with the size of the book, the machine being easily adjusted to accommodate books of different sizes.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a machine for applying stripping and constructed in accordance with my invention.

Figure 2 is a top plan view illustrating the machine.

Figure 3 is a transverse sectional view taken on the line 3—3 of Figure 1.

Figure 4 is a transverse sectional view taken on the line 4—4 of Figure 2.

Figure 5 is a transverse sectional view taken on the line 5—5 of Figure 2.

Figure 6 is a fragmentary sectional view illustrating the mounting of the knife and its drive connection with a stop shaft.

Figure 7 is a fragmentary transverse sectional view showing the leaves of a book passing through certain guides of the machine for adhering thereto to the binding material or stripping.

Referring in detail to the drawings, the numeral 5 indicates an elongated flat face and has formed upon the top face thereof a substantially T-shaped portion 6 providing a work rest and has on opposite sides thereof undercut shoulders 7 acting as a guide for a carriage 8. The rest 6 being of T-shape has the head portion A thereof of a length equal to the width of the base. The leg portion B, in which the undercut shoulders 7 are formed, has a width less than the width of the base.

The portions A and B present flat bearing surfaces which lie in the same horizontal

plane. The head portion A acts as a stop for limiting the sliding movement of the carriage in one direction of the base and has adjustably mounted on its top face opposed flat wear plates 9 which may be adjusted toward and from each other in accordance with the width of the binding strip employed. The opposed edges of the wear plates act as guides for the binding strip as it is moved over the top face of the rest 6.

The carriage 8 includes oppositely arranged guide plates 10 each of L shape and slidably engaging the shoulders 7 of the rest 6. Rising vertically from the guide plates 10 are pairs of supporting plates 11 and 12 which are secured thereto in any well known manner for releasably securing the carriage 8 on the rest. By backing off the set screws 13 the carriage 8 may be adjusted endwise of the rest.

The supporting plates 11 are provided with notches 14 in their upper ends and offset laterally from each other and receive pins 15 secured to ends of a reservoir 16. The pins fitting in the slots 14 and the latter being offset laterally will prevent the reservoir from tilting or tipping on the supporting plates 11 and will permit easy removal of the reservoir from the carriage when desired owing to the slots 14 opening outwardly through the upper ends of the supporting plates 11.

The under face of the reservoir 16 has secured thereon an absorbent material providing an applicator 17 which extends into the interior of the reservoir to become moist. A roller 18 is carried by the supporting plates 11 directly under the absorbent material 17 for the purpose of guiding the binding strip against said absorbent material so that the adhesive will become dampened or moistened. The binding strip is arranged in roll form, as shown at 19, and is supported by a shaft

20 fitting in notches 21 formed in the upper ends of the supporting plates 12. Drag plates 22 engage opposite sides of the roll of material 19 and are mounted on the shaft 20 and provided with notches 23 in the lower ends thereof to receive a rod 24 connecting the supporting plates 12. Nuts 25 are threaded on the shaft 20 and engage the drag plates, thereby permitting the drag plates to be adjusted relative to each other for accommodating rolls of binding material of different widths and for varying the pressure of the drag plates on the roll of the binding material supported by the shaft.

It is to be understood that the reservoir 16 has water therein for the purpose of moistening the material 17 and that the binding material has

adhesive material applied to one face thereof. In rolling the binding material in roll form the adhesive material is disposed uppermost as the binding material feeds off of the roll.

The wear plates 9 have slots 26 opening outwardly through edges thereof to receive set screws 27 that thread into the rest 6 or the head portion A thereof whereby the wear plates may be adjusted toward each other and from each other and removed when necessary.

Book guide plates 28 are adjustably mounted on the top faces of the wear plates and may be adjusted toward and from each other to accommodate books of different thicknesses and each is of substantially L-shape. The guide plates 28 have notches 29 opening outwardly through edges thereof to receive set screws 30 threaded into the wear plates 9 whereby the guide plates 28 may be adjusted and removed when desired. The binding strip passing between the wear plates 9 and guided thereby passes under the book guide plates 28.

Combined guide and folding plates 31 are mounted on the base 5 to the left of the rest 6 and each is of elongated formation and of L-shape in cross section. Pairs of brackets 32 and 33 are employed for adjustably mounting the plates 31 on the base and permit said plates 31 to be adjusted toward and from each other to accommodate books of different thicknesses. The ends of the plates 31 remote from the plates 28 are equipped with bowed pressure exerting spring fingers 34 through which the book may pass on leaving the plates 31 to apply additional pressure against the binding strip or the portions thereof engaging the outermost leaves of the book.

The brackets 32 are of substantially L-shape equipped with notches 35 to receive set screws 36 threaded into the base. The pair of brackets 33 are also provided with notches indicated by the character 37 to receive set screws 38 threaded in the base 5. The brackets 32 and 33 being thus connected to the base will permit the plates 31 to be easily adjusted toward and from each other and still kept in parallelism.

The brackets 33 are of a shape, as shown in Figure 4, so that they may support auxiliary guide plates 39 in a plane above the plates 31. By referring to Figure 4 it will be seen that the plates 31 form rests to engage the binding strip to bring about folding of the binding strip against the outside leaves of the book as the latter is forced downwardly between the plates 31, the book being guided by the plates 39 as it leaves the plates 28 and after a certain movement of the book endwise of the plates 31 it becomes disengaged from the guide plates 39.

The vertical edges of the guide plates 39 opposing the guide plates 28 are flared outwardly so that the book may readily move between the guide plates 39 on moving from between the guide plates 28.

A fixed knife blade 40 traverses the base between the head portion A of the rest and the plates 31, the upper edge of which is in a plane slightly below the plane of the horizontal portions of the plates 31 and the top face of the portion A of the rest 6 so that the binding strip may pass thereover.

The knife blade 40 forms a part of a bracket 41 fixed on the base 5. The bracket 41 rotatably supports one end of a shaft 42, the other end of the shaft being rotatably supported by a bracket 43 mounted on the base 5. The shaft 42 has

fixed thereto a gear 44 which meshes with a gear 45. The gear 45 is secured to a short shaft 46 journaled in the bracket 41 and has secured thereto a movable knife 47 provided at one end thereof with a handle 48. The gear 45 is preferably splined on the shaft 46 and has bearing thereagainst a coil spring 50 acting to tension the movable knife 47 with the fixed knife blade 40. Threaded on the shaft 46 is a nut 51 engaging the other end of the spring. The shaft 46 may have a limited sliding movement in the bracket 41 as well as being rotatable in the bracket so that the spring 50 may tension the movable knife with respect to the fixed knife blade so as to assure a shearing action between the movable knife and the fixed knife blade during the pivotal movement of the knife blade.

An adjustable book stop 54 is adjustably secured to the shaft 42 and is adapted to rotate with the latter and may be adjusted endwise of said shaft for operation in conjunction with books of different sizes. The mounting of the stop 54 on the shaft is such that the stop will transverse and rest on the plates 31 when the knife is disposed vertically as shown in Figure 1 and as the knife is moved into operative or horizontal cutting position, the stop 54 is swung upwardly to allow a book to pass on its movement from between the plates 31 and the spring fingers 34.

In operation, after the binding material has been brought across the roller 18 with its adhesive surface disposed uppermost it is fed along the rest 6 until the free end of the binding material is adjacent to the fixed knife blade 40. Portions of the binding strip will be disposed under the guide plates 28, as clearly shown in Figure 2. A partially constructed book, consisting of leaves arranged in book formation and stapled together is then positioned between the guide plates 28 as shown in dotted lines in Fig. 1 with the stapled edges of the leaves against the adhesive surface of the binding strip. The book of leaves is then slid to the left in Fig. 1, causing the strip of binding material to move therewith and enters between the guide plates 39 with the strip of binding material contacting the upper surfaces of the plates 31. This movement of the book of leaves is continued until the book of leaves abuts the stop arm 54. The knife blade 40 is then swung downwardly severing the strip of binding material to a length proper for the book. The downward movement of the knife blade 40 elevates the stop arm 54, so that the book of leaves may be moved further to the left in Fig. 1. At this time the operator presses the book of leaves downwardly between the plates 31 and at the same time with a movement to the left. The downward movement of the book of leaves between the plates 31, brings about folding of the strip of binding material against the outer leaves of the book. During the continued movement of the book of leaves to the left the spring fingers 34 force the folded portions of the strip of binding material tightly against the outer leaves so as to firmly adhere the binding material thereto when the book of leaves passes between the spring fingers. After this operation has been completed the knife is returned to a vertical position bringing the stop 54 into a lowered position ready for the operation on the next partially constructed book.

The carriage 8 being adjustable on the rest 6 may be adjusted endwise thereof so that when different size books are being acted upon the carriage can be adjusted into a position so that an

excessive amount of the binding strip will not be exposed beyond the moistening pad and become dry before use.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a device of the character described, a base, a flat rest on said base, a carriage carried by said rest and adjustable endwise thereof, means on said carriage to support a roll of adhesive tape for feeding over and in engagement with the rest and to be engaged by leaves in book formation manually moved endwise of the rest, a moistener on the carriage engaged by the tape prior to the leaves engaging said tape, folding plates on the base in a plane below the rest to receive therebetween the leaves manually moved from the rest and acting to fold portions of the tape on said leaves during the manual movement of the leaves relative to said plates, guide plates adjustable relative to each other for guiding the leaves during movement relative to the rest, said folding plates acting to guide the leaves during the manual movement thereof relative to said folding plates.

2. In a device of the character described, a base, a flat rest on said base, a carriage carried by said rest and adjustable endwise thereof, means on said carriage to support a roll of adhesive tape for feeding over and in engagement with the rest and to be engaged by leaves in book formation manually moved endwise of the rest, a moistener on the carriage engaged by the tape prior to the leaves engaging said tape, folding plates on the base in a plane below the rest to receive therebetween the leaves manually moved from the rest and acting to fold portions of the tape on said leaves during the manual movement of the leaves relative to said plates, guide plates adjustable relative to each other for guiding the leaves during movement relative to the rest, said folding plates acting to guide the leaves during the manual movement thereof relative to said folding plates, and spring fingers on said folding plates to engage the folded portions of the tape and press the latter against the leaves during manual movement of said leaves from said folding plates and relative to said fingers.

3. In a device of the character described, a base, a flat rest on said base, a carriage carried by

said rest and adjustable endwise thereof, means on said carriage to support a roll of adhesive tape for feeding over and in engagement with the rest and to be engaged by leaves in book formation manually moved endwise of the rest, a moistener on the carriage engaged by the tape prior to the leaves engaging said tape, folding plates on the base in a plane below the rest to receive therebetween the leaves manually moved from the rest and acting to fold portions of the tape on said leaves during the manual movement of the leaves relative to said plates, guide plates adjustable relative to each other for guiding the leaves during movement relative to the rest, said folding plates acting to guide the leaves during the manual movement thereof relative to said folding plates, spring fingers on said folding plates to engage the folded portions of the tape and press the latter against the leaves during manual movement of said leaves from said folding plates and relative to said fingers, and a manually operated cutting means including fixed and movable blades between the rest and said folding plates.

4. In a device of the character described, a base, a flat rest on said base, a carriage carried by said rest and adjustable endwise thereof, means on said carriage to support a roll of adhesive tape for feeding over and in engagement with the rest and to be engaged by leaves in book formation manually moved endwise of the rest, a moistener on the carriage engaged by the tape prior to the leaves engaging said tape, folding plates on the base in a plane below the rest to receive therebetween the leaves manually moved from the rest and acting to fold portions of the tape on said leaves during the manual movement of the leaves relative to said plates, guide plates adjustable relative to each other for guiding the leaves during movement relative to the rest, said folding plates acting to guide the leaves during the manual movement thereof relative to said folding plates, spring fingers on said folding plates to engage the folded portions of the tape and press the latter against the leaves during manual movement of said leaves from said folding plates and relative to said fingers, a manually operated cutting means including fixed and movable blades between the rest and said folding plates, a shaft rotatable by said movable blade and journaled on the base, and a stop arm secured to the shaft to traverse the folding plates during one position of the movable blade and to assume a position vertically of the folding plates during a second position of the movable blade.

OTTO W. SUTTER.
